UNITED STATES PATENT OFFICE.

JOHN TYLER WHITTLE, OF BALTIMORE, MARYLAND, ASSIGNOR OF ONE-HALF TO JEROME I. VOGELER, OF SAME PLACE.

TUMBLER-WASHER.

SPECIFICATION forming part of Letters Patent No. 289,737, dated December 4, 1882.

Application filed April 14, 1883. (No model.)

To all whom it may concern:

Be it known that I, JOHN T. WHITTLE, of Baltimore city and State of Maryland, have invented a new and useful Improvement in 5 Tumbler-Washers; and I do hereby declare that the following is a full, clear, and exact description of the same, reference being had to the accompanying drawings, forming part of this specification, in which—

10 Figure 1 is a vertical central section, showing the position of the tumbler in dotted lines. Fig. 2 is a side elevation, showing the tumbler off and the discharge taking place through pipe *c*; and Fig. 3 is a horizontal section through the chamber *B*.

15 My invention relates to that form of tumbler-washer used by druggists for soda-water fountains, and at drinking-bars, and other like places, in which the tumblers are placed 20 upside down upon a rotary support which is depressed by the weight of the tumbler and made to open a valve which allows jets of water to play upon the inside of the tumbler to cleanse it, the valve being automatically closed 25 when the weight of the tumbler is removed. It has been customary to provide a series of 30 these washers connected with the same main supply-pipe, and when a number of tumblers were being washed and one was removed the closure of the valve involved an increased 35 pressure on the valves of the others, that interfered with the action of the others and sometimes closed them prematurely.

The object of my invention is to provide 40 such a construction of washer as shall avoid such interference, and shall also permit the tumblers to rotate more freely without the clogging of the rotary support and facilitate the cleaning of the same, as will be fully described hereinafter.

In the drawings, *A* represents the lower 45 part of the case of one of the washers, which section of case connects with one of the branch pipes of the main supply-pipe. In the bulb 50 or enlarged portion of this part of the case is arranged a valve-seat, *a*, which is formed in a cross bar or support, *b*, and which valve-seat forms the upper opening of a vent-tube, *c*, that passes from the concentric valve-seat to the exterior of the case.

On top of the section *A* of the case is screwed

another section, *B* *B'*, made in two parts, screwed together, the lower one of which is formed with a stem, *g*, having a central hole passing entirely through the same, and which two sections together form an annular chamber, *d*. To this annular chamber there are inlet- 55 orifices *e* below, and outlet orifices *f*, through which latter the water issues in jets upon the tumbler. Through the central tubular stem, *g*, there plays a valve-stem, *C*, bearing on its lower end a valve, *D*, that closes over a seat, *h*, surrounding the orifices *e*, and the lower portion, *i*, of which valve is round or conical and adapted to fit the subjacent valve-seat *a* 60 at the top of the vent-tube *c*. This valve is normally drawn up, so as to cover and close the orifices *e* and open the vent-tube *a*, and this position is maintained by the tension of a spiral spring, *j*, wound around the projecting 65 upper end of the valve-stem, and the pressure of which spring is regulated by a screw-nut, *k*, against which the upper end of the spring bears.

70 *E* is the revolving turn-table or rotary support for the tumbler, which is pivoted upon the projecting end of the valve-stem. Heretofore the rotary support has been made with the stem, so as to turn with it, and this involved the friction of the stem, preventing 75 sensitiveness of action, making the joint liable to become clogged, so that it could not turn, and involving great difficulty in cleaning out such accumulation. By placing the rotary support on the top of the valve-stem, so as to 80 turn on the latter, these difficulties are entirely avoided, the turning of the tumbler is sensitively effected, and the said support can be readily taken off and cleaned.

85 The operation of my device is as follows: Assuming that all of the washers are provided 90 with tumblers and the valves *D* depressed by the weight of the tumblers, as in Fig. 1, the vent-tube will be closed by the conical end *i* of valve *D* and the orifices *e* will be opened, 95 and water will then pass around the cross-bar *b* and vent-tube *a*, and, entering the holes *e*, will pass to the annular chamber of the upper part of the case, and thence issues through the jet-orifices *f* against the inside of the tumblers, and as the jet-orifices are arranged inclinedly, so as to throw the jets obliquely 100

against the sides of the tumblers, the latter are free to respond on their sensitive rotary supports and rotate therewith. Now, if one or more of the tumblers be removed for use, 5 as in Fig. 2, the rotary support of that washer being relieved of the weight of the tumbler, the spiral spring forces up said support and valve-stem and the valve D on the lower end of the latter rises and closes the orifices e, while 10 its round or conical end i at the same instant and by the same movement rises from the valve-seat of the vent-tube, and the water then, instead of being cut off, is simply diverted from the orifices e to the vent-tube, and 15 the result is that although the jets from orifices f cease to play a uniform flow of water continues, and there is no increased pressure brought upon the other tumbler-washers to produce objectionable results, as would be the 20 case if the water were cut off absolutely.

I am aware that a single automatic relief-valve has been provided for a series of tumbler-washers which opened when the pressure exceeded a given limit, and I do not claim 25 such arrangement.

Having thus described my invention, what I claim as new is—

1. A tumbler-washer having a feed-opening for the jets and a vent or discharge opening, combined with a valve operating alternately to open the one and close the other, 30 substantially as described.

2. The case-section A, with discharge-tube having a concentric valve-seat, combined with the case-section B B', having feed-openings e 35 and f, and the valve-stem C, with valve D, acting alternately to close the feed-openings and open the discharge, substantially as described.

3. The combination, with the case of a tumbler-washer and a valve-stem projecting 40 through and above it, of a detachable turn-table or rotary support pivoted or mounted to turn upon the external end of said stem, as and for the purpose described. ④

JOHN TYLER WHITTLE.
